UNITED STATES PATENT OFFICE.

RICHARD SHELTON RICHESON, OF ST. LOUIS, MISSOURI.

DESIGN FOR A VEHICLE-BODY.

42,075.

Specification for Design.

Patented Jan. 2, 1912.

Application filed October 31, 1911. Serial No. 657,862. Term of patent 7 years.

To all whom it may concern:

Be it known that I, RICHARD SHELTON RICHESON, a citizen of the United States, residing at St. Louis, State of Missouri, have invented a new and original and ornamental Design for Vehicle-Bodies, of which the following is a specification, reference being had to the accompanying drawing, forming a part thereof.

Figure 1 is a side view of a vehicle body,

showing my new design; Fig. 2 is a front view of the same; and, Fig. 3 is a rear view.

I claim:—

The ornamental design for a vehicle body, as shown.

RICHARD SHELTON RICHESON.

Witnesses:

J. Wm. REILY,

J. A. SAUL,

CAROLYN DE VELLING.
